SHINGLE

Albert J. Anderson, Ansonia, Conn., assignor to
J. E. Smith & Co., Inc., Waterbury, Conn., a
corporation of Connecticut

Application June 8, 1936, Serial No. 84,196

4 Claims. (Cl. 108—8)

This invention relates to new and useful improvements in shingles generally, although more particularly to shingles of the rigid composition type such as asbestos.

5 Among the several objects of my invention are to provide a rigid shingle which can be manufactured without waste; to provide such a shingle which can be used for roofing or siding work; to provide such a shingle which may be laid in 10 courses of different head laps; to provide such a shingle which may be easily centered, and to provide such a shingle with nail openings which will be covered by the top shingles and which 15 will avoid the nails passing through the subjacent shingles.

With these and other objects in view which will more fully appear, the nature of the invention will be more clearly understood by following the description, the appended claims, and the 20 several views illustrated in the accompanying drawing.

In the drawing:

Figure 1 is a plan view showing the method employed in cutting shingles of my invention from 25 an indeterminate length of stock,

Figure 2 is a plan view showing a plurality of my improved shingles positioned for side wall covering,

30 Figure 3 is a similar view but showing the shingles positioned for roof covering, and

Figure 4 is a perspective view of one of the shingles.

Like reference numerals designate corresponding parts throughout the several figures of the 35 drawing.

My improved rigid composition shingle A is of inverted T-shape and comprises a body which includes a butt portion 5 having side edges 5^a, 5^b, and an extension portion 6 of exactly half 40 the width of the butt portion and connected centrally to the latter to form resultant butt ends 7, 7 which project beyond the side edge portions 8, 8 of the extension portion 6, said edge portions being disposed in parallel relation and

45 in planes at right angles to the upper edge portions 9, 9 of the butt ends 7, 7. The shingle also includes fillets 10, 10 which are located between the extension portion 6 and the butt ends 7, 7, and have inclined edges 11, 11 which merge with the side edge portions 8, 8 of the extension portion and the upper edge portions 9, 9 of the butt portions. The upper corners of the extension portion 6 are inclined or beveled as at 12, 12 and these inclined edge portions merge with the top

edge 13 of the shingle at points equidistant from the vertical center line of the shingle and also merge with the side edge portions 8, 8. The angles of inclination of the inclined edge portions 11 and 12 are identical, and the lengths of these two inclined edge portions are equal. The combined length of the edge portions 9, 9 is equal to the total length of the top edge portion 13.

5 Nail openings 14, 14 which are formed in the shingle body are located at the intersections of lines extending from the side edge portions 8, 8 and the upper edge portions 9, 9.

A slot 15 which is employed as a centering means when laying the shingles, projects downwardly from the top edge portion 13 and is centrally located with respect to the side edge portions 8, 8.

20 My improved shingle is cheap to manufacture as the shingles are complementary and consequently there is no waste in the cutting as shown in Fig. 1. These shingles are cut from an indeterminate length of stock whose width is equal to the combined height of two shingles or to any multiple thereof.

25 From the foregoing it will be observed that the shingle may be used for either siding or roofing work; that when used for siding work the head lap is greater than when used for roofing work and that the shingles may be laid in courses of different head laps in order to give a variation in exposure and to thereby locate the lines of courses even with the window sills and window frame headers or other horizontal obtrusions; that the shingles may be readily centered by arranging the side edges of the butt portion in alignment with the notches of subjacent shingles; and that the nail holes of subjacent shingles are covered by the top shingles, and that by reason of the beveled courses of the extrusion portions the nails will not pass through the subjacent shingles when the shingles are being employed either for roofing work or siding work.

30 It is of course to be understood that the details of structure and arrangement of parts may be variously changed and modified without departing from the spirit and scope of my invention.

45 I claim:

1. A rigid inverted T-shaped shingle comprising a body including a butt portion (5) and an extension portion (6) of exactly one-half the width of the butt portion and projecting centrally therefrom to form resultant butt end portions (7, 7), the side edge portions (8, 8) of the extension portion being disposed in planes at right

5 angles to the upper edge portions (9, 9) of the butt end portions, said body including fillets (10, 10) merging with the side edge portions (8, 8) and the upper edge portions (9, 9), the upper corners (12, 12) of the extension portion being inclined and merging with the top edge (13) of the extension portion and with the side edge portions (8, 8) thereof, the angles of the edges (11, 11) of the inclined fillets (10, 10) and the edges of the inclined corners (12, 12) being alike, and the combined length of the upper edge portions (9, 9) of the butt end portions being equal to the total length of the top edge (13) of the extension portion (6).

10 2. A rigid inverted T-shaped shingle comprising a body including a butt portion (5) and an extension portion (6) of exactly one-half the width of the butt portion and projecting centrally therefrom to form resultant butt end portions (7, 7), the side edge portions (8, 8) of the extension portion being disposed in planes at right angles to the upper edge portions (9, 9) of the butt end portions, said body including fillets (10, 10) merging with the side edge portions (8, 8) and the upper edge portions (9, 9), the upper corners (12, 12) of the extension portion being inclined and merging with the top edge (13) of the extension portion and with the side edge portions (8, 8) thereof, the angles of the edges (11, 11) of the inclined fillets (10, 10) and the edges of the inclined corners (12, 12) being alike, and the combined length of the upper edge portions (9, 9) of the butt end portions being equal to the total length of the top edge (13) of the extension portion (6), the body having a centering slot (15) extending downwardly from the top edge (13) of the extension portion and located centrally with respect to the side edges (5^a, 5^a) of the butt portion (5).

15 3. A rigid inverted T-shaped shingle comprising a body including a butt portion (5) and an extension portion (6) of exactly one-half the width of the butt portion and projecting centrally therefrom to form resultant butt end portions (7, 7), the side edge portions (8, 8) of the extension portion being disposed in planes at right

20 angles to the upper edge portions (9, 9) of the butt end portions, said body including fillets (10, 10) merging with the side edge portions (8, 8) and the upper edge portions (9, 9), the upper corners (12, 12) of the extension portion being inclined and merging with the top edge (13) of the extension portion and with the side edge portions (8, 8) thereof, the angles of the edges (11, 11) of the inclined fillets (10, 10) and the edges of the inclined corners (12, 12) being alike, and the combined length of the upper edge portions (9, 9) of the butt end portions being equal to the total length of the top edge (13) of the extension portion (6), the body portion having a pair of nail holes (14, 14) located at the intersections of lines 25 extending from the side edge portions (8, 8) and the upper edge portions (9, 9).

25 4. A rigid inverted T-shaped shingle comprising a body including a butt portion (5) and an extension portion (6) of exactly one-half the width of the butt portion and projecting centrally therefrom to form resultant butt end portions (7, 7), the side edge portions (8, 8) of the extension portion being disposed in planes at right angles to the upper edge portions (9, 9) of the 30 butt end portions, said body including fillets (10, 10) merging with the side edge portions (8, 8) and the upper edge portions (9, 9), the upper corners (12, 12) of the extension portion being inclined and merging with the top edge (13) of the extension portion and with the side edge portions (8, 8) thereof, the angles of the edges (11, 11) of the inclined fillets (10, 10) and the edges of the inclined corners (12, 12) being alike, and the combined length of the upper edge portions (9, 9) of the 35 butt end portions being equal to the total length of the top edge (13) of the extension portion (6), the body having a centering slot (15) extending downwardly from the top edge (13) of the extension portion and located centrally with respect to the side edges (5^a, 5^a) of the butt portion (5), the body portion having a pair of nail holes (14, 14) located at the intersections of lines 40 extending from the side edge portions (8, 8) and the upper edge portions (9, 9).

45 ALBERT J. ANDERSON.
